UNITED STATES PATENT OFFICE.

OTTO A. KREUTZBERG, OF LAKE BLUFF, ILLINOIS.

PULVERIZING-MACHINE.

1,368,636.

Application filed November 8, 1919, Serial No. 336,581. Renewed July 8, 1920. Serial No. 394,803.

Specification of Letters Patent. Patented Feb. 15, 1921.

To all whom it may concern:

Be it known that I, OTTO A. KREUTZBERG, a citizen of the United States, residing at Lake Bluff, in the county of Lake and State 5 of Illinois, have invented certain new and useful Improvements in Pulverizing-Machines, of which the following is a specification, reference being had to the accompanying drawings, forming a part thereof.

10 The purpose of this invention is to provide an improved machine for pulverizing hard materials. It consists in the elements and features of construction shown and described, as indicated in the claims.

15 In the drawings:

Figure 1 is a plan view of a machine embodying this invention.

20 Figs. 2 and 3 are sections transaxial with respect to the two coöperating rotary members of the machine, at two different relative positions of said two members.

Fig. 4 is a rear side elevation of one of said rotary members.

25 Fig. 5 is a section at the line, 5—5, on Fig. 4.

Fig. 6 is an edge view of one of the rotary members having the parts of which it consists adjusted in a special way.

30 Fig. 7 is a face view of one of the rotary members showing a slightly modified construction.

The drawings show a pulverizing machine of a type which in certain respects is familiar, comprising two frusto-conical disks 35 or pulverizing wheels, A and B, mounted upon parallel axes for rotation of their frusto-conical surfaces in contact or close proximity, and provided with means (not shown) for rotating them toward each other 40 at their proximate sides—that is, in opposite directions about their axes, for engaging and crushing and grinding between them the material which is introduced between their said proximate revolving surfaces. In machines 45 of this character the crushing and grinding of material submitted to the machine is effected by drawing the fragments which are to be crushed between the rolls, down between them at their proximate sides revolving toward each other; and this is effected partly by gravity causing the fragments to descend in the narrowing gap between the two revolving bodies, and partly, and more especially, by the frictional engagement of 50 the revolving bodies with the fragments as

they are lodged upon their revolving surfaces. Particles which are small enough to descend between the two revolving and approaching surfaces very near to their line of tangency are engaged by these surfaces at a 60 very favorable angle for holding them, because the surfaces approach parallelism as they approach the line of tangency and thereby engage the interposed particles by almost direct pressure toward each other against 65 said interposed particles; but larger particles which become lodged upon both the two revolving bodies at a distance back from their line of contact are much less favorably situated for being engaged, because at such 70

distance back from their tangential contact line or line of greatest proximity, the two revolving surfaces are at a considerably wide angle to each other and tend to wedge the interposed body back away from their tangential line. It thus happens that a comparatively large fragment contained in a stream of smaller fragments which is delivered to the revolving bodies for being crushed and ground, will become thus engaged against 80

the bodies so that they do not grip it and draw it in between them, but so that it continues to ride upon them while they revolve under it, and several such larger bodies becoming thus lodged and engaged without 85

being drawn in, stop the entire stream of incoming material, or a large portion thereof, and thereby reduce the capacity of the machine for its purpose. The purpose of said invention is to overcome this difficulty and 90 to cause larger fragments as well as smaller to be gripped by the revolving bodies even when they are of such size as to lodge upon said bodies at a distance away from the tangent line so as to make the angle of engagement very wide. This result is effected by 95

making one of said revolving bodies with a portion of its conoidal face projected off abruptly from the remainder, so as to form a shoulder or step from the offset portion to 100 the remainder, which will permit particles at least of as great a diameter as the depth of such shoulder to fall between the two revolving surfaces substantially to the tangential line, so as to be there gripped by the 105 direct pressure between them, as will be understood from Fig. 2; and also to cause larger particles which cannot by this expedient fall so deeply between the two revolving bodies, but which may be lodged 110

upon them at a distance back from their tangent line to be gripped between them by the sudden approach of the two bodies to each other which will occur when the shoulder 5 passes the tangential line, it being understood that the two disks are pressed toward each other by very strong springs C, for the purpose of gripping between them the material to be crushed. Also the shoulder may 10 be formed by offsetting one part with respect to the other so that the shoulder faces forward in the direction of rotation of the disk having this shoulder, *i. e.*, toward the line of meeting; so that particles lodged between the two bodies at a considerable distance back from their tangent line and not gripped frictionally by them because of the 15 bad angle at which they are lodged thereon will nevertheless be engaged positively by the advancing shoulder, and positively forced through between the two disks, with the effect of crushing them if the pressure is adequate to do so. This may be understood from Fig. 2 in which the offset to form the shoulder faces toward the tangent line of the 20 two disks.

A preferred construction of disk for the purpose of producing the offset and shoulders described is that shown in the drawings, in which the disks, both of which are 30 shown with the frusto conical facing composed of two parts, one of which may be offset from the other, comprise a flat-faced member, 1, on which there are mounted two 35 halves of a frusto-conical member, one of said halves, *a*, being permanently secured to the base member, while the other half, *b*, is attached thereto by means of headed screws, 40 *c*, set loosely through the base member and screwed into the said segment, *b*, so that the screws serve to draw the segment back toward the base; and another set of screws, *d*, is provided screwed through the base and impinging upon the back of the segment, so 45 that they serve to force the segment away from the base. By the adjustment of these two sets of screws, the segment may be rigidly set at any distance within the range of operation of the screws off from the base, 50 and thereby caused to present its conoidal grinding surface projected beyond and offset from the conoidal surface of the other half, *a*, of the disk. This forms two shoulders, *x* and *y*, at diametrically opposite positions. And it will be understood that as the 55 two disks, one of which does not have and the other which does have the offset portions described, are revolved for engaging material between them and are pressed toward each 60 other by the springs, C, one of the shoulders will revolve facing away from the line of tangency or line of contact of the two rolls, as seen in Fig. 3, while the other will revolve facing toward said line of contact as seen 65 in Fig. 2. One of the shoulders will there-

fore operate upon and engage the fragments as first above described,—that is, by permitting the fragment to drop between the two disks nearer to the line of tangency and onto or nearly to the shoulder, so that it 70 will be engaged between the two disks with pressure almost directly toward each other, preventing any possibility of the fragment from escaping or being wedged back from between the rows, and insuring its being 75 crushed when the pressure is adequate to crush it. The other shoulder will engage fragments as secondly above described and as seen in Fig. 2; that is, to say, fragments of any size becoming lodged 80 between the two disks will be encountered by the advancing shoulder and positively engaged thereby and forced out between the two disks with the desired crushing effect if the pressure is adequate. In 85 the first instance, when the shoulder has revolved past the line of tangency, the two disks will approach each other abruptly and thereby tend to engage between them fragments which might otherwise not be engaged, or will crush, as by a hammer blow, 90 fragments which are lying between them but are not being frictionally engaged adequately to draw them in for crushing at the tangent line. 95

For certain materials and under certain circumstances, it may be found desirable to protrude the movable segments in such manner as to form prominently only one of the two shoulders described,—that is, inclinedly 100 with respect to the base, as seen in Fig. 6, which will cause the shoulder at one side to be of zero height at the outer circumference and comparatively negligible at the inner circumference, while the other shoulder will 105 taper widening from the inner to the outer end.

In some cases it may be desirable to produce both shoulders, but both facing in the same direction, and for that purpose one 110 half of the disk entire cone frustum which is to be provided with such shoulders is made adjustable along the diametric plane of severance between the two halves as seen in Fig. 6. For this purpose the construction 115 may be to form the base member with slots, 1^a, located parallel to the line of severance between the two halves of the disk, the movable half being secured to the base by headed bolts taking through said slots and engaging 120 said movable half, the bolts being set tight to hold the movable half at its position of adjustment for producing the shoulder.

In practice for operating on hard material, a shoulder $\frac{1}{16}$ th of an inch in height is 125 adequate to give the desired result. When the half, *b*, of the frusto-conical facing which is advanced becomes worn by reason of its taking the greater part of the work, it will be set back to the base, and the other 130

half will then be found to be protruding and forming the desired shoulders.

I claim:—

1. In a pulverizing machine, in combination two rotary bodies and means for revolving them with their surfaces of revolution proximate and revolving toward each other at their proximate sides, one of said bodies having its said surface of revolution at a segment thereof offset from the path of revolution of the remainder in a direction for closer proximity of at least a portion of said offset segment to the other of said revolving bodies.
2. In the construction defined in claim 1, the revolving bodies being each frusto-conical and their conoidal faces being those revolving in proximity, and the offsetting of the offset segment of one of them being effected by advancing said offset segment axially toward the other body.
3. In the structure defined in claim 1, the offsetting of the offset segment being ef-

fected by advancing said offset segment toward the other body at one end only of said segment.

4. In the structure defined in claim 1, the revolving bodies being frusto-conical the one having the offset segment comprising a flat-faced portion upon which said offset segment portion is mounted, the means for so mounting being a set of set screws set through said base portion and screwed into the segment, having heads which are stopped outside said base portion, whereby they are adapted to draw the segment back toward the base, and another set of screws screwed through the base member and impinging upon the back of the segment, whereby they are adapted to force the segment away from the base.

In testimony whereof, I have hereunto set my hand at Chicago, this 31 day of October, 1919.

OTTO A. KREUTZBERG.
